UNITED STATES PATENT OFFICE

JAMES E. MORANO, OF HAMMONTON, NEW JERSEY, ASSIGNOR OF ONE-THIRD TO
ANTHONY DE MARCO, OF HAMMONTON, NEW JERSEY

CRANBERRY GATHERER

Application filed April 20, 1927. Serial No. 185,232.

It is the purpose of the present invention to provide, in a cranberry gatherer a vacuum passage operatively mounted on a wheel supported frame with its nose in close proximity to the cranberry bog, with a suction fan at the opposite end, to create a vacuum in said chamber for drawing the cranberries therethrough.

The invention has for its purpose to provide severing means at the nose of the vacuum chamber including gathering fingers, to comb through the twigs and vines, the severing means acting to cut the vines and twigs, and thereby leaving the berries free to be drawn through the vacuum chamber, the nose of the chamber being supported by runners, which are capable of adjustment for regulating the height of the nose relative to the cranberry bog, and hence govern the effectiveness of gathering the berries.

Another purpose is to provide a conduit in which the vacuum passage or chamber is formed, said conduit being in two sections, the nose carrying section being adjustable, so that the nose of the conduit can be regulated in its height with respect to the cranberry bog.

Another purpose is to provide yieldable means for the adjustable section as well as guiding means therefor.

Still another purpose is the provision of means within the rear portion of the vacuum chamber acting to beat the cranberries, not enough to injure them, but sufficiently tending toward removing them from the twigs or other branches, there being means for screening the branches and twigs from the cranberries.

It is the aim to provide a wheel supported frame mounted on and in advance of a conventional motor driven vehicle chassis, with means operatively connecting with the motor of said vehicle, so as to in turn operate the different severing means, one being at the nose of the chamber and the other just in the rear of the berry beating means, and for operating the beating device as well as the suction fan.

It is to be understood that the particulars herein given are in no way limitative, and that

while still keeping within the scope of the invention, any desired modification of details and proportions may be made in the construction of the appliance according to circumstances.

55

The invention comprises further features and combination of parts to be hereinafter set forth, shown in the drawings and claimed.

In the drawings:—

Figure 1—is a view in side elevation of the improved cranberry gatherer constructed in accordance with the invention.

Figure 2—is a plan view of the same with a part thereof broken away.

Figure 3—is a sectional view on line 3—3 of Figure 2.

Figure 4—is a detail sectional view on line 4—4 of Figure 1.

Figure 5—is a sectional view on line 5—5 of Figure 1.

70

Figure 6 is an enlarged detail view of one side of the structure shown in Figure 4, more clearly showing the operating means for the severing device in the rear part of the vacuum chamber.

75

Figure 7—is an enlarged view of a portion of the severing device which is adjacent the ends of the conduit which has the vacuum passage or chamber.

Referring to the drawings, 1 identifies a frame or chassis which is an extension of or may be applied to the conventional chassis of a motor driven vehicle 2, the general construction of which is not shown but simply indicated. A motor 3 is provided, and its drive shaft 4 has a worm 5, which through the medium of a worm wheel 6, operates a shaft 7. The shaft 4 of the motor carries and operates a suction fan 8, which is operatively mounted in a suction fan casing 9, the casing being mounted upon the frame 1 as disclosed in Figure 1.

85

The shaft 7 is mounted in suitable bearings 11 and carries a sprocket 10 on one end. The sprocket 10 operates a chain 10a, which in turn operates a sprocket 12, which is on a shaft 13, which is mounted in a suitable bearing of the side of the machine. The shaft 13 carries a worm wheel 14 which meshes with a worm 15 on a shaft 16. This

95

100

shaft 16 has an eccentric 17 with an eccentric strap 18, there being a rod connection 19 between the strap and the reciprocating cutter bar 20 of the severing device 21 positioned within the vacuum chamber of the conduit. The severing device includes a plurality of cutters 22 and is located adjacent a series of screening bars or rods 23. The screening bars or rods are arranged on an angle in the vacuum chamber 24 of the conduit 25. The screening bars are provided for the purpose of screening the small twigs and branches from the berries as they are drawn into the vacuum chamber. With the berries, as they are drawn into the vacuum chamber, there is a relatively small quantity of twigs drawn into the chamber. Such twigs being relatively small and lighter than the berries, therefore the berries will reach a beater, which will act to remove the berries from the vacuum chamber. Those of the twigs that will not pass between the bars or rods 23 will naturally guide toward the cutters 22, where the twigs will be further chopped, and since they are relatively light they will be drawn beyond the screening bars or rods 23.

The lower part of the rear portion of the wall of the vacuum chamber is provided with a semi-cylindrical housing 26, which contains an elongated beater 27 operatively mounted upon a shaft 13. This beater comprises a plurality of longitudinally disposed blades which act to remove the berries from the vacuum chamber. However, the berries that may remain on some of the twigs when drawn into the vacuum chamber, are caused to be detached from the twigs due to the action of the beater on the berries, which berries are permitted to discharge through an opening 29 in the lower part of the housing 26 and into a receptacle 30, which may be supported upon the frame 1 of the apparatus. The shaft 16 is mounted in bearings 31, and its forward end has a universal connection 32 with the end of a shaft 33. The shaft 33 is in turn connected by a universal joint 34 to another section of shaft 35, the lower forward end of which carries a bevel gear 36 which in turn meshes with a smaller gear 37 on a shaft 38 which has an eccentric disk 39 connected by a link 40 to a reciprocating cutter bar 41, which is associated with a plurality of cutters 42. The fingers 42 are located adjacent the nose of the conduit 25, which conduit extends forwardly over the frame 1 and is downwardly positioned, so that the nose thereof is in close proximity to the cranberry bog. The cutters 42 are designed to be positioned from the surface of the ground sufficiently to lift the vines, so that the cutter bar 41 will only cut the twigs of the upper parts of the cranberry bog, and as the machine travels forward the cutters 42 tend to comb the berries

from the bog, that is comb them off, in order that they may be more readily drawn into the conduit through the medium of the vacuum in the vacuum chamber. As the cutters perform this function the cutter bar is reciprocating, acting to chop twigs that break loose from the cranberry bog and hook around the cutters 42. The aim is to keep the fingers clean from these twigs and vines. Naturally, as there is a vacuum created in the chamber there are a certain amount of twigs and vines drawn with the berries into said chamber, and these are carried rearwardly through the chamber and are screened from the berries, and those twigs which reach the cutters 22 are further chopped adjacent the rear lower portion of the screening rods, and drawn beyond said rods.

The forward wall of the conduit just immediately above the ends thereof, is provided with projecting lugs or bearings 43, and these lugs have guides 44, in which the upright arms 45 of the runners 46 are guided. The upright arms 45 having a plurality of grooves 47, and threaded in the lugs or bearings 43 are set bolts 48 which may be adjusted to engage the grooves 47 and thereby hold the arms 45 in different adjusted positions, and yet allow the arms to swivel, while the runners 46 will accommodate themselves to the direction in which the apparatus is guided.

The conduit 25 consists of two sections, a stationary section 49 and a movable or tiltable section 50, the latter being hingedly mounted at 51 to the stationary section 49. Where the section 50 is pivoted it has a telescopic union 52 with the stationary section, so as to permit the section 50 to be raised and lowered, and yet retain the chamber 24 completely closed and thereby preventing the vacuum ceasing.

To guide the section 50, which is of arcuate form and tapered, a suitable frame 53 is mounted upon the frame or chassis 1 of the apparatus. This frame 53 is supported in an inclined position as shown in Figure 3 and straddles the section 50 of the conduit 25. It is re-inforced by means of a brace 54, and secured by clamps 55 on the section 50 are transverse rods 56 and 57, one on top of the section 50, the other on the bottom thereof. Each rod consists of two sections 58 joined together by a turnbuckle 59. The remote ends of the rods 56 and 57 are forked and journaled therein are rollers 60 which ride on the upright side bars of the frame 53, more clearly shown in Figure 5. By this construction the section 50 of the conduit may be guided in its tilting movement. To permit this movement to be of a yieldable character tension coil springs 61 are attached at 62 to the transverse portion of the guide frame 53, and in turn are connected at 63 to the sides

of the section 50 of the conduit. It is to be noted that the section 50 may yield and re-seat itself, and since it is supported by the runners 46, it may accommodate itself to the irregularities of the cranberry bog, or other surface which the apparatus may traverse.

The frame or chassis 1 is mounted upon conventionally supported wheels 65, and has a side platform 66, and as shown in Figure 2, the conduit with its chamber is to one side of the frame or platform 1, thereby leaving substantial room on the platform or frame to carry baskets of cranberries, or other articles, or on which an operator may ride. The conduit is supported by uprights 67, and rising from one side of the conduit is an upright arm 68 provided with several openings or apertures 69, and a bar 70 is fastened at 71 to the section 50 of the conduit and extends rearwardly, so as to cross or intersect the arm 68. The bar 70 has a plurality of apertures 72, any one of which may register with one of the openings or apertures 69, so as to receive a pin or the like, so as to support the section 50 of the conduit in a raised position.

In the operation the machine traverses the cranberry bog, the nose of the section 50 of the conduit passing over and somewhat adjacent the tops of the vines of the cranberry bog, the runners sliding over the top of the bog. The runners are to be adjusted to regulate the position of the nose of the section 50 of the conduit. The suction at the nose of the section 50 of the conduit lift the vines (not enough to pull them out of the ground or break them off at the root), and then the fingers or cutters 42 comb the berries off the vines as the machine goes forward. The suction created at the nose of the section 50 of the conduit draw the berries up through the conduit and into the vacuum chamber. The bar 41 in its association with the fingers 42 act to keep the fingers clean, by cutting the twigs and the small parts around the tops of the vines. The cranberries are drawn through the conduit to the vacuum chamber, and such twigs as may be drawn into the vacuum chamber with the berries are screened from the berries by the bars or rods 23, while the berries are beaten or removed from the rear part of the vacuum chamber through the medium of the beater 27 and discharged through the opening 29. Those of the twigs that are not screened from the berries by the bars 23 move toward the rear until they reach the cutters 22, where they are finely chopped, and being lighter than the berries are drawn beyond the rods. The twigs when carried beyond the rods are discharged as at 73, while the berries when removed from the vacuum chamber pass through the opening 29 to a box or other receptacle 30.

It is to be noted that the shaft 33 consists of two sections 33a and 33b, which are united by a slip joint 33d which is rectangular in

cross section so that the two sections will rotate as one shaft, but are capable of longitudinal movement relative to each other, thereby allowing for the raising and lowering movement of the section 50 of the conduit.

The invention having been set forth, what is claimed is:

1. In a cranberry gatherer, a wheel supported frame having a conduit mounted thereon and provided with a vacuum chamber, the forward end of the conduit having a pivoted section disposed to partly telescope within said conduit, said pivoted section being positioned over the front end of the machine and having a suction nose to lift the vines of the bog, means carried by the pivoted section and associated with and adjacent the suction nose to ride over the bog and thereby govern the position of the suction nose with reference to the vines of the bog, means for combing the berries from the vines, whereby they may be drawn into the conduit at the suction nose, means for cutting the twigs and keeping the combing means clean, screening rods in the rear of the vacuum chamber to screen the twigs from the berries, the rear portion of the vacuum chamber having an offset compartment, a beater in said compartment for removing the cranberries from the vacuum chamber, said compartment having a discharge opening for the cranberries, and means at the lower portions of the screening means for chopping the twigs allowing them to be drawn beyond the screening means.

2. In a cranberry gatherer, a wheel supported frame having a conduit mounted thereon and provided with a vacuum chamber, the forward end of the conduit having a pivoted section disposed to partly telescope within said conduit, said pivoted section being positioned over the front end of the machine and having a suction nose to lift the vines of the bog, means carried by the pivoted section and associated with and adjacent the suction nose to ride over the bog and thereby govern the position of the suction nose with reference to the vines of the bog, means for combing the berries from the vines, whereby they may be drawn into the conduit at the suction nose, means for cutting the twigs and keeping the combing means clean, screening rods in the rear of the vacuum chamber to screen the twigs from the berries, the rear portion of the vacuum chamber having an off-set compartment, a beater in said compartment for removing the cranberries from the vacuum chamber, said compartment having a discharge opening for the cranberries, and means at the lower portions of the screening means for chopping the twigs allowing them to be drawn beyond the screening means, said pivoted section being yieldably supported, whereby the suction nose of the pivoted section may travel over

the surface of the bog and accommodate itself to the irregularities.

3. In a cranberry gatherer, a wheel supported frame having a conduit mounted thereon and provided with a vacuum chamber, the forward end of the conduit having a pivoted section disposed to partly telescope within said conduit, said pivoted section being positioned over the front end of the machine and having a suction nose to lift the vines of the bog, means carried by the pivoted section and associated with and adjacent the suction nose to ride over the bog and thereby govern the position of the suction nose with reference to the vines of the bog, means for combing the berries from the vines, whereby they may be drawn into the conduit at the suction nose, means for cutting the twigs and keeping the combing means clean, an arch fastened to the frame and engaging over the pivoted section, rods carried by the pivoted section with rollers at their ends to engage with the sides of the arch to guide the pivoted section in its movement, and yieldable means connected to the arch and the sides of the pivoted section to yieldably support the latter, whereby the suction nose may accommodate itself with relation to the top of the cranberry bog.
4. In a canberry gatherer, a wheel supported frame having a conduit mounted thereon and provided with a vacuum chamber, said conduit comprising a main rear section and a forward pivoted section, the latter partly telescoping within the former, said pivoted section having a suction nose at its lower forward end with means thereon for combing the berries from the vines, whereby they may be drawn into the conduit at the suction nose, a frame straddling the pivoted section and secured to the wheel supported frame, said straddling frame having guides, rollers carried by the pivoted section and engaging said guides, and yielding means operatively associated between the straddling frame and the pivoted section for yieldably balancing said pivoted section, whereby the suction nose of the pivoted section may accommodate itself to the surface of a cranberry bog.

In testimony whereof he affixes his signature hereto.

JAMES E. MORANO.
